COIN RECEIVING MECHANISM

John C. Nyberg, North Hollywood, Calif., assignor to Paramount Pictures Corporation, New York, N.Y., a corporation of New York

Filed Dec. 10, 1962, Ser. No. 243,239

6 Claims. (Cl. 194—102)

This invention relates to a mechanism for receiving coins and more particularly to improvements therein.

Those persons who are connected with coin vending mechanisms of the type where the public is invited to purchase an article or service by first depositing coins in a slot, are well acquainted with the fact that some members of the public deem it a challenge to be able to retrieve their coins from such mechanisms after once having inserted them into the coin receiving apparatus. A number of different techniques by such individuals are usually used, but the one which is most difficult to prevent, is the attachment of a string or a soft wire to a coin whereby after the coin has released the vending mechanism it can be pulled out of the slot into which it was inserted.

Accordingly, an object of this invention is to provide a mechanism for preventing coin retrieval once said coin is deposited into said mechanism.

Another object of this invention is to provide a unique coin receiving mechanism.

Yet another object of the present invention is the provision of a novel and useful coin receiving mechanism.

These and other objects of this invention may be achieved in a coin receiving mechanism in which the coin is inserted into the mechanism through a slot. The insertion of the coin actuates a bar which blocks further coin insertion until the coin processing operation has been completed. A lever is provided with this mechanism which must then be actuated. This lever actuates mechanism which carries the coin away from the coin slot over to another opening in the cash box. At the same time, the coin which has been deposited is sized. When the coin reaches the cash box it is allowed to fall into this cash box. By the time the coin reaches the cash box another coin carrying opening in the carrying member is positioned beneath the receiving coin slot and the bar which blocks this receiving coin slot is then removed.

The novel features that are considered characteristic of this invention are set forth with particularity in the appended claims. The invention itself, both as to its organization and method of operation, as well as additional objects and advantages thereof, will best be understood from the following description when read in connection with the accompanying drawings, in which:

FIGURE 1 is an isometric view illustrating equipment with which the coin receiving mechanism is employed.

FIGURE 2 shows a view of the coin receiving mechanism in accordance with this invention when looked at from one side.

FIGURE 3 is a view of the mechanism in accordance with this invention when seen from the opposite side to the one shown in FIGURE 2.

FIGURE 4 is a view in elevation of an embodiment of the invention shown in its initial or "at rest" operating position.

FIGURE 5 is a view in elevation of the embodiment of the invention shown in an intermediate operating position.

FIGURE 6 is a view of an embodiment of the invention as shown in the final position in the processing of a coin.

FIGURE 7 is a view in section along the lines 7—7 in FIGURE 4 showing various positions of the coin together with a coin blocking mechanism.

2

FIGURE 8 is a view in section along the lines 8—8 of FIGURE 7 also showing the operation of the coin blocking mechanism.

Referring now to FIGURE 1, there is shown an attachment 10 of a type with which the coin receiving mechanism in accordance with this invention may be employed. It is to be understood that the mechanism shown in FIGURE 1 is by way of illustration and not by way of limitation of the utility of this invention. The attachment shown in FIGURE 1 is one which is employed for converting a commercial television receiver to a receiver capable of receiving subscription television programs. Such apparatus is described in Patent No. 3,041,389 to Court et al. In accordance with such a system the price for a television program is transmitted to the attachment 10, which is connected to a television receiver. Such price is shown through a window 12, in the attachment. Money is deposited in the coin slot 14. Upon the deposit of any coin a lever 16 is actuated. The amount of money which is deposited is sized and the total of the value of the coins is shown in a credit window 18. When the amount in the credit window 18 equals the amount of the price 12, then the button 20 is pushed. Upon the occurrence of this, the receiver associated with the attachment can intelligibly reproduce the received program. The knobs 22 and 24 are respectively employed for selecting a channel having a program desired to be viewed and for controlling the volume of the sound which is reproduced. As indicated, the equipment briefly described in FIGURE 1, is merely by way of example of equipment which can use the coin receiving mechanism in accordance with this invention and should not be construed to limit the utility thereof.

The coin receiving mechanism is just underneath the coin slot 14, and the lever 16 constitutes a part thereof. FIGURE 2 is a side view of an embodiment of the invention. This constitutes a rotatably supported coin carrying member 30, which, broadly speaking, has the shape of a relatively smaller and larger disc, respectively 30A, 30B, separated by a thick hub 30C. The member 30 has eight coin slots, 32, which are angularly spaced at 45 degrees around the member 30. When a coin is inserted into the coin opening 14, it can then pass into the one of these coin slots positioned thereunder. The lever 16 is then moved in the direction shown by the arrow in FIGURE 2 which causes the coin receiving member 30 to be rotated approximately 22½ degrees, thus carrying the coin therewith out from under the coin slot 14. During this time the coin is being sized. When the lever 16 has been moved to its extremity of motion, the coin 34 will then drop into a second coin chute 31, which is positioned to receive it from the coin carrying member. The lever 16 is then released, and the coin carrying member 30 continues to rotate for another 22½ degrees approximately, thereby bringing a second one of the coin slots 32, into position under the coin opening 14.

FIGURE 3 is a view of the embodiment of the invention from the side opposite to the one shown in FIGURE 2. The lever 16 extends downward to a pivot 40 on which it is mounted. A spring 42 attached to the lever 16 biases the lever 16 to its initial position as shown in the drawings. A coin sizing member 44 is pivotably supported at a pivot point 46, which is mounted in the housing wall 36. A spring 48, biases the sizing member 44 so that it is urged to pivot in a clock-wise direction as shown on the drawing in FIGURE 3. It is prevented from doing this by a camming extension 50 which is supported in the lever 16. Accordingly, when the lever 16 is moved, after a coin has been deposited, the sizing member 44 follows to the lever 16. The following motion continues

until another extension of the sizing member, not shown, engages an edge of the coin which is in the coin slot in the coin receiving member 30. This stops the following motion of the coin sizing member 44. The configurations on the end of the coin sizing member 44 are then sensed by other apparatus not shown, in response to which the value of the coin may be detected and totalized with other coins previously deposited by mechanism, not shown.

FIGURES 4, 5 and 6 are views in elevation showing the various positions assumed by the embodiment of the invention respectively in the initial position prior to the insertion of a coin, in a position to which the apparatus is moved when the lever 16 is moved to its extreme position, and the position assumed when the lever has almost returned to its initial position. As may be seen from the views of FIGURES 4, 5, and 6 the periphery of the upper disc portion 30B, has a ratchet gear shape. There is shown a coin chute operating pawl 60, which is pivotably supported by the pivot 62. The coin chute operating pawl consists of a forked portion 60A which engages the lever 16 to be movable thereby. Suitably attached as by welds 64, 66, to the coin chute operating pawl, is a coin shield member 68. This coin shield member has a slot therein, which, in the initial position, aligns itself with the opening in the coin carrying member 30.

Broadly speaking, the coin chute operating pawl 60, comprises a V-shaped member with the pivot being at the base of the V and the coin shield 68 being attached to one arm of the V and the forked lever engaging portion 60A being formed at the other arm of the V. The ends of the V arms are formed into actuating pawls, respectively 60C and 60D. There is also an intermediate actuating pawl section 60E, which extends into the V from the arm of the V adjacent the forked portion 60A.

At the top of the coin carrying member 30, there are formed a number of camming projections 70. Eight of these projections are formed and they are equally spaced around the top of the coin carrying member. When the lever 16 is moved downward, it pivots the coin chute operating pawl 60 in a counter-clockwise direction. As a result, the coin shield 68 begins to move away from its position of alignment with the coin slot in the coin carrying member. The pawl tip 60E engages the camming surface 70 to rotate the coin carrying member in a clockwise direction. The pawl arm 60C next engages another one of the cam surfaces 70, to limit the extent of motion of the coin chute operating pawl 60. The limiting position assumed by this apparatus is shown in FIGURE 5. As may be seen there, the pawl tip 60E engages the camming surface 70 as does also the pawl tip 60C. The coin opening in the coin shield 68 has been moved until it is out of alignment with any coin slots 32, in the coin carrying member 30. The coin carrying member has also been rotated on the order of 22½ degrees, during which time the coin is being sized.

When the lever 16 is released, the spring 42 brings it back to its initial position. In doing this, the lever carries the coin chute operating pawl back with it. As shown in FIGURE 6, in the course of being restored to its initial position, the pawl tip 60D of the coin chute operating pawl 60, engages the camming extension 70 on the top of the coin carrying member, to rotate the coin carrying member another 22½ degrees. This rotation is in the same direction as was given to the coin carrying member when the lever was pulled down initially. At this time the coin slot and the coin carrying member have moved a total distance of 45 degrees from their initial position. A suitably positioned coin chute (shown in FIGURE 2) can then remove the coin from the coin carrying member. When the lever 16 has been returned to its initial position as shown in FIGURE 4, another coin can be inserted which will be entered into the next coin slot in the coin carrying member.

FIGURES 7 and 8 are two different views of a section of the embodiment of the invention for the purpose of showing the operation of the coin blocking mechanism. As shown in FIGURE 7, the coin 34 is inserted into the opening of the mechanism and comes to rest in a suitable opening in the coin carrying member. A coin blocking member 72, then senses the presence of a coin in the coin slot in the coin carrying member and moves a blocking bar 76 (see FIGURE 8) across the coin slot opening. The coin blocking member comprises a pivotably supported central portion 72M, having a sensing arm 74 extending therefrom. The sensing arm, as may be seen in FIGURE 8, is contacted by a coin which is deposited into the coin receiving member. This causes the coin blocking member 72, to pivot to bring the blocking bar 76 into position where it obstructs the opening into the coin receiving member. The coin blocking member stays in position until the lever 16 has moved the coin out of contact therewith, by which time the coin shield 68 has covered the opening and it is impossible to insert another coin thereinto.

There has accordingly been described and shown herein a novel, useful, coin receiving mechanism which covers the coin receiving opening in a manner to prevent the insertion of additional coins once the first coin has been inserted thereinto, until said first coin has been processed. In addition, the mechanism prevents the retrieval of a coin which has been inserted thereinto, despite the attachment of a wire or spring by carrying the coin to a position where intervening structures assure this.

I claim:

1. In apparatus of the type wherein coins are inserted into a coin receiving slot therein to effectuate a purchase, a coin receiving mechanism comprising a coin receiving chute displaced a predetermined distance from said coin receiving slot, a movable coin carrying member supported between said coin receiving slot and said coin receiving chute, said coin carrying member containing a plurality of coin carrying slots therein spaced twice said predetermined distance apart, means for supporting said coin carrying member with one of its coin carrying slots aligned with said coin receiving slot, means for moving said movable coin carrying member to move the coin carrying slot aligned with said coin receiving slot to alignment with said coin receiving chute, and thereafter to align the succeeding coin carrying slot to alignment with said coin receiving slot, a coin slot blocking member, and means supported between said coin receiving slot and said coin carrying member to block said coin receiving slot during motion of said coin carrying member.

2. In apparatus as recited in claim 1 wherein said coin slot blocking member comprises a flat member extending between said coin receiving slot and said coin carrying member, said flat member having a coin slot therein aligned with the coin receiving slot and the coin receiving slot in said coin carrying member, and means for moving said flat member with said coin carrying member to move its coin slot away from its aligned position until the succeeding coin carrying slot in said coin carrying member is aligned with the coin receiving slot.

3. In apparatus as recited in claim 1 wherein said coin carrying member comprises a rotatable member having the shape of two spaced disks separated by a thick hub and having a plurality of coin receiving slots equally spaced thereabout.

4. In apparatus of the type wherein coins are inserted into a coin receiving slot therein to effectuate a purchase, a coin receiving mechanism comprising a coin carrying member rotatably supported below and with one side adjacent said coin receiving slot, said coin carrying member comprising an upper and lower disc separated by a thick hub, a plurality of coin carrying slots equally spaced about said coin carrying member and each slot being oriented to be aligned with said coin receiving slot when said coin carrying member is rotated to place a coin carrying slot

thereunder, a coin receiving chute positioned adjacent the side of said coin carrying member which is opposite to the side adjacent said coin receiving slot, said coin receiving chute being disposed to be aligned with and to receive coins from a coin carrying slot which is moved half of the distance between coin slots away from said coin receiving slot, means for rotating said coin carrying member through the distance required to carry a coin carrying slot from alignment with said coin receiving slot to alignment with said coin receiving chute and then to align a succeeding coin slot with said coin receiving slot, and a flat member mounted on said means for rotating to be movable therewith, said flat member extending between said coin receiving slot and said coin carrying member and including a coin slot aligned with said coin receiving slot and a coin carrying slot only while said means for rotating is inactive whereby operation of said means for rotating blocks passage of a coin between said coin receiving slot and said coin carrying member.

5. In apparatus as recited in claim 4 wherein said means for rotating said coin carrying member comprises a

V-shaped member, pivotably supported at the apex of said V, a plurality of camming projections on the upper disc of said coin carrying member, a movable lever, means in one arm of said V-shaped member for engaging said movable lever to be pivotally movable as said lever is moved, and means on the ends of said V-shaped member for engaging the camming projections of said upper disc to rotate said coin carrying member in one direction as said V-shaped member is pivoted reciprocally by said lever.

6. In apparatus as recited in claim 4 wherein there is included adjacent said coin receiving slot means for blocking said coin receiving slot upon insertion of a coin into one of said coin carrying slots.
